United States Patent Office

Des. 201,777
Patented July 27, 1965

201,777

DESK SET BASE OR SIMILAR ARTICLE

William E. L. Bunn, Fort Madison, Iowa, assignor to W. A. Sheaffer Pen Company, Fort Madison, Iowa, a corporation of Delaware

Filed Nov. 9, 1964, Ser. No. 82,528

Term of patent 14 years

(Cl. D74—5

FIGURE 1 is a perspective view of a desk set base or similar article showing my new design;

FIG. 2 is a top plan view thereof;

FIG. 3 is an end elevation view thereof, and

FIG. 4 is a side elevation view thereof.

The essential features of the design are shown in solid lines.

I claim:

The ornamental design for a desk set base or similar article substantially as shown and described.
